(57) **CLAIM**

The ornamental design for an electronic device with animated graphical user interface, as shown and described.

DESCRIPTION

FIG. 1 is a front view of an electronic device with animated graphical user interface showing a first image of the claimed design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The outermost broken lines in the figures show an electronic device, and form no part of the claimed design. The other broken lines in the figures show portions of the animated graphical user interface that form no part of the claimed design.

The appearance of the animated images sequentially transitions between the images shown in FIGS. 1-6. The process or period in which one image transitions to another forms no part of the claimed design.
